BOTTLE CAP

Rudolph Sonnenberg, Belvidere, Ill., assignor to
Mid-West Bottle Cap Co., Belvidere, Ill., a cor-
poration of Illinois

Application June 24, 1938, Serial No. 215,566

4 Claims. (Cl. 213—38)

This invention relates to bottle caps and to methods for making same, and is directed primarily to caps of the type commonly formed of paper and used on milk bottles.

An important obstacle to the universal use of the type of milk bottle cap known as hood caps, that is, caps which cover the outer surface of the bottle neck, has been the matter of expense.

These caps have been expensive because of the material of the paper stock which it has been necessary to employ therein, because of the large amount of stock required, because of the expense relative to the application of these caps to the bottles, and because, in some instances, it has been expensive to recondition the bottles for subsequent use.

An important object of the invention is the provision of a cap of the character described which may be applied to the bottles at lesser expense than caps of the same class heretofore known.

Another object of the invention is the provision of a bottle cap which may be applied to the bottle with the same speed and facility as the standard form of cap.

Another object of the invention is the provision of a cap which involves no increase in the cost of reconditioning the bottle.

A still further object of the invention is the provision of a substantially waterproof cap which is self sealing and may be applied to the bottles by means of a machine capper.

I have also aimed to provide an improved method for making caps of the class described wherein the caps are formed from strip material by a consecutive series of cutting and forming operations, the caps being packaged substantially simultaneously with the last forming operation.

Other objects and advantages will appear from the following description and the accompanying drawings, in which—

Figure 1 is an expanded top view of one embodiment of my invention;

Fig. 2 is a fragmentary longitudinal section through a cap package, showing the caps stocked therein;

Fig. 3 is a fragmentary bottom view of a cap showing the pre-formed shape thereof;

Fig. 4 is a section through the neck of a milk bottle showing the manner in which the capping operation proceeds;

Fig. 5 is a fragmentary side view of a milk bottle showing the cap applied thereto;

Fig. 6 is a developed view along the line 6—6 of Fig. 5;

Fig. 7 is a section on the line 7—7 of Fig. 5;

Fig. 8 is a top view of the paper strip from which the cap shown in Figs. 1 and 2 are formed, showing the steps of the method;

Fig. 9 is a fragmentary section through the neck of the milk bottle showing a modified form of the cap applied thereto, which embodies my invention;

Figs. 10 and 11 are top views of a strip of stock showing the steps of methods for forming the caps shown in Fig. 9;

Fig. 12 is an expanded top view of a further embodiment of the invention;

Fig. 13 is a bottom view of the cap shown in Fig. 12 showing the manner in which the skirt is folded;

Fig. 14 is a fragmentary side view partly in section showing the cap applied to a bottle;

Fig. 15 is a developed view on the line 15—15 of Fig. 14, and

Fig. 16 is a section on the line 16—16 of Fig. 15.

Referring first to the embodiment shown in Figs. 1 to 8, inclusive, the invention contemplates a bottle cap of the so-called hood style, commonly known in the trade as a hood cap, though not necessarily limited thereto.

In this instance the cap is formed from a single piece of stock cut to a circular or disk-like shape 18, the disk having a laterally disposed tab 19 extending outwardly beyond the periphery of the disk to facilitate the removal of the cap from the bottle. Understanding of the structure of the cap will be facilitated by a description of the method of making the same, and reference is therefore had

to Fig. 8 in which the numeral 21 designates a strip of sheet stock of suitable width for cutting out the disks in a manner shown. In this instance the strip 21 is formed of paper having a coating of a material known as "Paraseal," which

is a composition formed of rubber and paraffin wax such as described in Patent 2,054,114. I do not, however, wish to limit myself to this specific composition, since any sheet may be employed which has sufficient strength, imperviousness to water, and which has surfaces which will adhere either

under mild heat and pressure or under either of these forces. I have, however, found the above described material to be admirably suited to the purpose, and prefer to have the paper sheet coated on only one side, which is the side opposite to that shown in Fig. 8.

In making the cap I first cut the stock into strips of suitable width such as shown at 21 and form therein spaced registering holes on oppo-

site sides of the strip as shown at 22 and 23 for

the purpose of accurately locating the strip during the successive operations to be performed thereon. Thereafter if desired I impress at spaced points on the strip suitable indicia as indicated at 24 preferably by printing, this indicia frequently being in part decorative and also bearing the name of the dairy or other desired printed information. The impressions are spaced along the strip at such points that they will fall in the center of the cap subsequently formed therefrom. Preferably, though not necessarily, the printing may be performed at a time prior to the die operations and the material rolled up into rolls preparatory to the cutting and forming operations.

The cutting and forming operations are preferably performed successively as a continuous operation, the strip passing step by step through successive dies spaced apart so that the strip progresses in step fashion through the various die operations, the strip being located in each die by means of the holes 22 and 23. In the first die operation a plurality of V-shaped scores 25 are formed in the sheet radially about the printed indicia 24, this scoring being produced merely by pressing along the dotted lines as indicated at 25 for the purpose of causing the material to bend freely along these lines. In the next die operation as shown at 26, the periphery of the disk is cut completely through the material as shown at 27, the shearing operation being interrupted at spaced points as shown at 28 so that the disk will not be completely severed from the strip. This peripheral cut also extends around the tab 19 and intersects the longer legs 29 of 30 the scoring 25. In the next die operation indicated at 31, arcuate cuts as shown at 32 are formed extending inwardly from the peripheral cut 27, beginning at the junction between this cut and the longer score marks 29 and extending 35 through an arc to the outer ends of the shorter score marks 33 of the V-shaped scores 25. In the final die operation indicated at 34, circular spaced score marks 35 are formed concentric with the peripheral cut 27 in the material of the disk, these score marks being of a diameter to define the top edge of the bottle so as to cause the disk to bend smoothly over the end of the bottle forming in effect a skirt for the cap which comprises that portion of the cap from the score marks 35 to the peripheral or marginal cut and which contains the score marks 29 and 33 and the cuts 32. During this die operation the disk thus formed is pressed laterally so as to break the uncut portions 28 and sever the cap from the remainder of the strip, and simultaneously with this severance the skirt is formed by folding this portion of the disk laterally into the position shown in Fig. 2, the stock between the score marks 29 and 33 folding inward as shown in Fig. 3. At the conclusion of this die operation the completed cap is moved upward facing Fig. 8 into a cylinder indicated by the numeral 36, the cylinder 36 being a shipping and dispensing package and serving to retain the caps in the shape shown in Fig. 2. By thus packaging the caps as a part of the final die operation which serves to tightly nest the caps together in a tube or other package, I am enabled to compactly pack the caps and avoid relative movement between the various caps which might tend to cause interlocking of the caps and thereby interfere with the proper functioning of the feeding mechanism in the automatic capper. In other words, the feeding mechanism of the

capper must select the caps one at a time and this is not conveniently possible if the caps so interlock that they do not come away from the stack one at a time. This interlocking may be caused by relative rotation as between the caps of a stack, and I avoid any possibility of this action by packing the caps directly as a part of the last die operation and inserting the packing thus formed directly into the capping mechanism.

Referring now more particularly to Figs. 1 and 3, it will be seen that during the forming operation the skirt bends along the scored lines 29 and 33 so that the section of material indicated by the numeral 37 which is positioned between these scored lines rotates inwardly along the scored line 29 so that in the completed cap it rests in a plane approaching right angles with respect to the remainder of the skirt. It will also be observed that the arcuate cuts 32 form a plurality of toes 38 which move inward under the adjacent part of the skirt as shown at 39 and rest against the inner surface of the skirt.

In the form shown in Figure 1 I have provided twelve folds, and while the exact number of folds is not critical, the number should not be excessive because a suitable amount of overlap should be provided to make a good seal. This will vary with the size of the cap and will normally lie between about seven and fifteen folds. Small folds of crimp-like nature should be avoided.

Referring now to Fig. 4, I have therein shown the manner in which the cap is applied to a milk bottle. The neck of the milk bottle is designated by the numeral 41 and the bottle has the conventional disk 42 inserted therein and forming the primary seal or cap for the bottle. During the capping operations the hood cap is dropped over the mouth of the bottle as shown in this figure. Thereafter a portion of the capping mechanism herein shown in dotted lines and including a rubber or other resilient cup 43 and actuating arms 44 and 45 spaced circumferentially of the cup, move downward over the cap until the lower edge 46 of the cup is below the marginal edge of the cap. The arms 44 and 45 are then moved inward flexing the sides of the cup, causing the portions 31 of the skirt to collapse and pressing the material upon itself in this area. At the same time the toes 38 are moved inward and compressed against the portions 39 of the skirt, the whole skirt portion being compressed between the sides of the cup and the outer surface of the bottle. Heating means are provided either in the cup 43 or the arms 44 for the purpose of heating these parts and transmitting the heat to the skirt. It will be seen that the heat sensitive material is on the inner surface of the cap so that when the cap is pressed against the bottle in the manner described, the overlapping or folded portions of the skirt will adhere, and when the cup 43 is removed, the cap will remain in the position shown in Figs. 5 to 7, inclusive, thus forming a waterproof hood over the outer end of the bottle.

Important features of the invention are the fact that the toes 38 fold under the adjacent part of the skirt so that they present no obstacle to the downward passage of the cup 43 as it passes over the cap during the capping operation, and to the arcuate shape of the upper edge of these toes which, in case of an accident such that the toe should fold onto the outer side of the cap, permit the cup to slide down over the toe

without catching thereon and severing the toe from the cap. Another important feature is the fact that the scores 39 are so positioned that when the skirt is folded against the side of the bottle by downward movement of the cup 43, the edge of the flap formed thereby is parallel with the longitudinal center line of the bottle so that the downward movement of the cup 43 may be straight, and when this element is moved down straight, that is, parallel with the longitudinal center line on the bottle, no relative movement is required as between the score lines 29 and the sides of the cup to produce proper folding. These features materially facilitate the capping operation and render the use of a cap of this character commercially practicable. In other words, through the use of these and other features the capping operations are rendered better than 99.9% perfect, below which no cap can be long commercially successful. Furthermore, it permits of convenient hand capping where this may be necessary.

Directing attention now more particularly to the forms shown in Figs. 9 to 11, inclusive, this form while embodying substantially the same invention as in the previous form, has certain characteristics rendering it more desirable for certain purposes. This form is characterized by the fact that the conventional disk bottle cap such as shown at 42 in Fig. 4 is placed on the outer side 30 of the hood cap, and the central portion of the hood cap seats down into the neck of the bottle against the cap retaining shoulder. Likewise, the method of making the cap varies somewhat because of the different form, though in general following the same steps as shown in Fig. 8. In this instance the first step is the cutting of the holes 22 and 23. In this instance, because of the insertion of a printed disk, the indicia 24 is not impressed directly on the strip. The second step as indicated at 47 is the impression of the scoring 25 including the score lines 29 and the score lines 33. The next step as indicated at 48 is the cutting of the periphery 27, again leaving the uncut portions 28 as described in connection with Fig. 8. As the next step in the method as indicated at 49, a paper disk 51 is inserted under the die in this position, the paper disk bearing suitable indicia on its upper surface and where necessary or desired the lower surface may be coated with a suitable glue or adhesive. The next step of the method as indicated at 52 is the step of making the arcuate cuts 32 and where necessary applying pressure to the disk 51 for the purpose of causing it to adhere. The final step of the method as indicated at 53 includes the same operations as indicated at 34 in connection with Fig. 8, with the exception that in this instance the die, instead of forming the annular scores 35, forms a central recess in the disk as best indicated at 54 in Fig. 9, simultaneously forming a plurality of small pleats 55, the concluding operation of this step being to move the completed cap into the cylindrical package 36 as heretofore described.

An alternative method of making this cap is shown in Fig. 11, which is identical with that shown in Fig. 10, except for the elimination of the step designated by the numeral 49 and the combination of this step with step 53. In the method shown in Fig. 11 the strip material 21 comprises a strip of paper having the so-called "Paraseal" coating which is substantially non-adhesive at normal atmospheric temperatures but develops its adhesive properties at atmospheres somewhat above 100° F. and considerably below 75

the boiling point of water. Using this material for the disk 51, the cap may be made by employing the steps first of forming the holes 22 and 23, thereafter forming the scoring 25 in a step designated by the numeral 56, subsequently forming the peripheral cuts 27 in a step indicated by the numeral 57, thereafter forming the cuts 32 in a step indicated by the numeral 58, and in a final step 59 inserting the disk 51 formed of the above described material and having the adhesive coating on its lower surface, between the dies. In this instance the upper member of the die is heated sufficiently to cause adherence of the disk to the upper surface of the hood sheet. Likewise, in this instance, the die is so shaped as to depress the central portion of the hood cap as shown at 54 and forming the pleats 55. These operations are pre-formed at this station and by a single set of dies in addition to the functions performed in the method shown in Fig. 8.

Referring now to Fig. 9, the hood cap is of substantially the same form as that shown in Fig. 4, with the exception that the disk 51 is seated on the outer surface of the central portion 61 of the cap, and the cap is shaped so that the central portion and the disk 51 will seat down against the cap retaining shoulder 62 normally present on milk bottles. The skirt of the cap is identical with the form shown in Figs. 1 to 7, inclusive, and functions in like manner.

In Figs. 12 to 16, I have shown a further embodiment of the invention wherein the cap is formed from a circular sheet of material and is produced entirely through forming and scoring operations without resort to cutting the periphery thereof. In this instance the disk or sheet is provided with circular spaced scoring lines 63 concentric with the periphery of the sheet and of a diameter to be received against the upper end of the bottle neck defining the central portion 64 of the cap and the skirt portion 65 thereof. The skirt portion has annularly spaced pairs of scoring lines 66 extending from edge to edge thereof and diverging scoring lines 67 and 68 forming wedge-shaped folding portions 69 and 71 on opposite sides of each pair of scoring lines 66. This arrangement of scoring is repeated around the periphery of the skirt, and the skirt is formed or bent at the scoring line to produce the structure shown in Fig. 13. This cap is applied to the bottle in the same manner as that shown in Fig. 4 and by means of the same equipment, and when applied, the skirt is folded in the manner shown in Figs. 14 to 16, inclusive. In this instance the adhesive, which is preferably the "Paraseal" material previously described, may be positioned on either or both sides of the sheet. It will be seen that when the adhesive is positioned on the inner surface of the cap, the inner surfaces of the overlapping portions 69 and 71 will adhere against the inner surfaces of a portion 72 formed by the creasing lines 66. On the other hand, if the adhesive is on the outer surface of the cap, the outer surfaces of the folded portions 69 and 71 will adhere to intermediate portions 73 of the cap skirt. In either case the periphery of the skirt will be confined against the outer surface of the bottle below the bead 74 thereof as shown in Figs. 14 and 16. Where both sides of the sheet carry adhesive, the opposite sides of the folded portions 69 and 71 will adhere to the portions 72 and 73 making a stronger seal, as will be evident.

Attention is directed to the fact that in the last described form of the invention the scoring

lines 66 are so located that as the skirt is folded about the neck of the bottle, these lines fall parallel with the longitudinal center line of the bottle and parallel with the direction of travel of the cup 43, so that as the cup moves downward over the neck of the bottle, these scoring lines tend to produce the proper folding of the partially pre-formed skirt.

While I have thus described and illustrated specific embodiments of the invention, I do not wish to be limited except as required by the prior art and the scope of the appended claims, in which—

I claim:

1. The combination in a bottle cap of the character described of a sheet of paper-like material having an adhesive surface scored and folded into a cup shape, said sheet having a central portion and an annular skirt, said skirt having annularly spaced arcuate cuts extending in a somewhat radial direction across a portion of the width of the skirt defining toes, and a plurality of scores defining folded areas, said scores being positioned on the skirt so that the exterior edge of the folds is parallel with the longitudinal center line of the bottle when applied thereto, the skirt being folded with the toes underlying the skirt.

2. The combination recited in claim 1 wherein adhesive is positioned solely on the inner surface 30

3. The combination in a bottle cap of the character described of a cup-shaped sheet of paper-like material having an adhesive surface, said sheet having an effectively flat central portion adapted to seat against the shoulder of a milk bottle, a peripherally raised portion for reception against the inner walls of the bottle and a depending skirt portion, said skirt having annularly spaced arcuate cuts extending in a somewhat radial direction across a part of the width of the skirt defining fastening toes, and score lines converging from the ends of said cuts to a point near the periphery of said central portion to define folds in the skirt, the skirt being folded with the toes underlying the skirt to adhere to the inner side of the skirt when the latter is gathered around the neck of a bottle, and a disk seated against the exterior of said central portion and within said peripherally raised portion.
4. The combination in a bottle cap of a disk-like sheet of paper shaped to overlie the mouth of the bottle and enclose a portion of the neck thereof having a heat sensitive waterproof coating, said sheet having annularly spaced arcuate cuts approaching tangential relationship with radii of the sheet forming toes, said sheet being formed to fold with said toes extending against the inner side of the sheet.

RUDOLPH SONNENBERG.
